UNITED STATES PATENT OFFICE.

GEORGE F. BUTTERFIELD, OF WEST NEWTON, MASSACHUSETTS, ASSIGNOR TO GRACE L. BUTTERFIELD, OF WEST NEWTON, MASSACHUSETTS.

COMPOSITE BOOT AND SHOE.

1,111,437.

Specification of Letters Patent. Patented Sept. 22, 1914.

Application filed July 10, 1913. Serial No. 778,273.

To all whom it may concern:

Be it known that I, GEORGE F. BUTTERFIELD, of West Newton, in the county of Middlesex and State of Massachusetts, have 5 invented certain new and useful Improvements in Composite Boots and Shoes, of which the following is a specification.

The object of this invention is the production of an efficient waterproof shoe with a 10 limited amount of rubber in its sole portion, applied in vulcanizable condition and shell-like form, and none whatever in the vamp or upper to interfere with foot ventilation. The composite structure of my improved 15 shoe is admirably adapted to accomplish the ends desired. Its characteristic features will be first described with reference to the accompanying drawing in which—

Figure 1 is a longitudinal section and Fig. 20 2 is a bottom plan of my improved shoe. Fig. 3 is a transverse section thereof and Fig. 4 a sectional representation of the parts to be assembled.

The composite boot or shoe has a suitable 25 vamp or upper, 7, preferably of leather or canvas, a lining 8 of thin cotton and an inner sole 9 of heavy textile fabric, friction-coated with rubber cement or vulcanizable rubber on its under side, for permanent adhesion when vulcanized to the parts immediately beneath it. Between the upper 7 and lining 8 at their lower edges, where they turn inwardly under the margins of the textile inner sole 9, I introduce a thin strip, 30 say one inch wide, of rubber binding 10, which extends somewhat above the inner sole and all around its sides and forward portion, such strip being coated on both sides with rubber cement so as to give an absolutely water tight joint. Below the textile inner sole 9 is a thin layer or sheet 11 of vulcanizable rubber, coming into immediate contact with the cement coated under side 35 of said inner sole and with the inward turned edges of the vamp or upper 7. At this stage the sheet or layer 11 extends, marginally, considerably beyond the insole and upper, around the entire bottom of the shoe.

A felt middle sole 12 here shown as having a substantial boss or heel shaped protuberance 13, of less size than an ordinary heel, is applied immediately beneath the layer 11, first being thoroughly coated all over by immersion in rubber cement until 55 saturated. The protuberance or heel boss

13 may be formed integral with the felt middle sole or secured to it by sewing or otherwise. It forms a light and cheap filling for the shell-like body of the heel portion of the outsole, thus saving cost and 60 weight of rubber. The seam 15, Fig. 1, which extends around the entire bottom portion of the shoe, firmly unites the inner sole 9, the vamp 7 and lining 8, the binding strip 10 between them, the thin rubber sheet 65 11 and the felt middle sole 12, all being pressed and drawn into close contact while the surfaces are adhesively coated as stated,—the shoe in process being mounted upon a last as will be understood. 70

The felt middle sole 12 and the heel boss 13 have a contour similar to that of the outsole but are of less area than the latter. The projecting margins of the rubber sheet or layer 11 may be turned down and under 75 the outer edges of the middle sole 12, with the coated surfaces of which said sheet will readily unite in vulcanizing. This would give a rubber binding to said edges of the felt middle-sole and aid in the adhesion of the outer sole when applied. The preferred construction, however, is shown in Figs. 1 and 3, where the margins of the rubber layer 11 are turned down outside, rather than inside, of the upright edge-wall of the heel and sole.

The outer sole or shoe bottom 14 is of shell-like form, its entire margin being raised above its sunken interior so as to surround and protect the thickened felt middle 80 sole and heel-boss and to merge, in vulcanizing, with the downward-turned margins of the rubber sheet or layer 11. This gives the effect or appearance of a heavy rubber sole while, owing to the felted interior, the shoe is unusually light. Moreover it furnishes a substantial edge wall of rubber for the composite sole.

The shoe bottom 14, complete, is formed of vulcanizable rubber, shaped in a suitable 100 mold and vulcanized while the other parts of the composite shoe are held fast upon it during the operation by suitable clamping mechanism, the various rubber and rubber-coated parts being thereby permanently 105 bonded by the heat and pressure essential to the process of vulcanization. Thus the sheet 11 and all other rubber parts are vulcanizable when first assembled, but, in the completed shoe, are vulcanized together. The

tread surface of this shoe-bottom 14 is peculiar in two respects, as indicated in Fig. 2. The marginal portion of its tap-sole is notched or scored with short, parallel, transverse channels *c*, in order to give greater flexibility to the sole and relieve the strain on said portions in walking. Also the inclosed portion of the tread surface, indicated by the elongated diamond forms *d*, is made somewhat crowning or higher along its central line to give a cushioned or resilient tread and increased wearing service as well as to avoid slipping. These features, while desirable in a boot or shoe, are not herein claimed.

I claim as my invention:

1. A composite boot or shoe, comprising an upper, an inner sole, a felt middle sole saturated and thoroughly coated with rubber cement, and a rubber outsole constructed and arranged to cover the bottom surface and peripheral edge of said middle sole, and stitching permanently uniting the middle sole marginally to the inner sole and upper, the various parts of said shoe being united by vulcanization.

2. A composite boot or shoe, comprising an upper, an inner sole, a felt middle sole

and heel boss saturated and thoroughly coated with rubber cement, and a rubber 30 outsole constructed and arranged to cover the bottom surface and peripheral edge of said middle sole, and stitching uniting the middle sole marginally to the inner sole and upper, the various parts being permanently united by vulcanization.

3. A composite boot or shoe, comprising a suitable upper and lining with an interposed binding strip of rubber along their lower edges, a rubber surfaced textile inner 40 sole, a felt middle sole saturated and thoroughly coated with rubber cement, a vulcanized rubber sheet interposed between said textile and felted soles and stitching uniting such soles marginally to the upper and 45 lining and a shell-like rubber outsole constructed and arranged to cover the bottom surface and inclose the peripheral edge of said felted middle sole, the various parts being permanently united by vulcanization.

In testimony whereof I have affixed my signature, in presence of two witnesses.

GEORGE F. BUTTERFIELD.
